BUILT-IN ELECTRIC TOASTER

Norman A. Beam, Boonville, Mo., assignor to McGraw-
Edison Company, Milwaukee, Wis.

Filed Sept. 21, 1972, Ser. No. 290,943

Term of patent 14 years

Int. Cl. D7—02

U.S. Cl. D7—93

FIG. 1

FIG. 2

FIG. 3

FIG. 4

FIG. 5

FIG. 1 is a top and left side perspective view of the built-in electric toaster shown withdrawn in operating position from its receiving shell, the rear part of which shell is adapted to be received in an opening in a building wall and the front part of which shell is adapted to project then forwardly of the wall;

FIG. 2 is a top and right side perspective view of the built-in electric toaster of FIG. 1, except shown in storage non-operating position inside its receiving shell;

FIG. 3 is a top plan view of the built-in electric toaster shown in FIG. 1;

FIG. 4 is a front elevational view of the built-in electric toaster shown in FIG. 1; and

FIG. 5 is a right side elevational view of the built-in electric toaster shown in FIG. 1.

The bottom of the built-in electric toaster is plain and unornamented.

I claim:

The ornamental design for a built-in electric toaster, substantially as shown and described.
